UNITED STATES PATENT OFFICE.

GEORGE O. BRISTOW, OF CUERO, TEXAS.

RAILWAY-CROSSING.

1,076,405.

Specification of Letters Patent. Patented Oct. 21, 1913.

Application filed January 23, 1912. Serial No. 672,907.

To all whom it may concern:

Be it known that I, GEORGE O. BRISTOW, a citizen of the United States, residing at Cuero, in the county of De Witt and State 5 of Texas, have invented new and useful Improvements in Railway-Crossings, of which the following is a specification.

This invention relates to improvements in railway crossings.

10 In carrying out my invention it is my purpose to provide a crossing which will permit the rolling stock to pass thereover without the jar and shock caused by the wheels passing the broken portions of the crossing 15 over which the bearing faces of the wheels pass in the ordinary construction of crossings.

I also aim to provide a crossing which is connected with the main rails of the track 20 and auxiliary rails, said auxiliary rails being adapted to form bearings for the flanges of the wheels of the rolling stock, so that the bearing surface of the wheel is raised above the track proper, whereby the said rolling 25 stock will pass over the crossing without shock or jar.

I also propose to provide an auxiliary track with a simple and effective means whereby the same may be shimmed to compensate for any wear which may occur incident to the rolling stock passing thereover.

With the above recited objects, and others of a similar nature in view the invention resides in the construction, combination and arrangement of parts, set forth in and falling within the scope of the appended claims.

For the purpose of explaining the invention the accompanying drawings illustrate a satisfactory reduction of the same to practice but the important instrumentalities thereof may be varied, and so it is to be understood that the invention is not limited to the specific arrangement and organization shown and described.

45 In the drawings, Figure 1 is a top plan view of a double crossing provided with my improvement. Fig. 2 is a sectional view upon the line 2—2 of Fig. 1. Fig. 3 is a detail perspective view illustrating two of 50 the rightangularly arranged tracks provided with my improved auxiliary rail. Fig. 4 is a detail perspective view of a modified form

of a main rail which may be employed, showing the auxiliary rail positioned thereon. Fig. 5 is a transverse sectional view of 55 the same. Fig. 6 is a top plan view of a single crossing. Fig. 7 is a sectional view upon the line 7—7 of Fig. 6. Fig. 8 is a transverse sectional view of a modification of Fig. 4.

60 Referring now to the drawings in detail, the numeral 1 designates an ordinary crossing, the same comprising longitudinally extending rails 2, and transverse intersecting rails 3. Both the rails 2 and 3 are, of course 65 formed in sections, that is spaces or openings 4 and 5 are provided by the rails at the points of intersection, and the said openings are adapted to serve as passages through 70 which the flanges of the wheels of the rolling stock may pass. In a crossing as just described, it is obvious that the bearing faces of the wheels passing over the crossing are not provided with a continuous bearing surface; that is, when the said 75 wheels pass over the spaces or cut away portions 4 and 5, a shock or jar is occasioned, and when the said wheels pass over one of the rail sections to the second rail section in 80 contacting with the edge or end of the second rail section both the bearing faces of the wheels and the ends of the rail sections of the crossing are liable to damage, and as a consequence are rendered comparatively 85 shorthived.

The numeral 6 designates the auxiliary rails which are secured to the inner faces of the main rails. These rails taper gracefully from their opposite ends and their points of connection with the main rails, and as a 90 consequence the flanges of the wheels of the rolling stock bear upon the said auxiliary rails and elevate the bearing faces of the said wheels to raise the same slightly above the main rails. The auxiliary rails provide continuous bearing surfaces and in no wise interfere with the main rails, so it will be seen 95 that the rolling stock can pass over the crossing quietly and without jar.

In some instances, and as illustrated in 100 Figs. 4 and 5, I provide a crossing constructed of rails of a peculiar formation. The said rails comprise a head or tread 7 having the inner face thereof rabbeted to

form a continuous rightangular depressed portion 8. The main body, or lower portion of the rails is enlarged and flares outwardly from its rightangular groove 8 to provide 5 an enlarged base 9. The inner face of the said base is preferably scalloped as designated by the numeral 10, the same being provided to afford a certain amount of elasticity as well as to permit the crossing to be 10 firmly secured within the road bed.

The numeral 11 designates the auxiliary rail which is positioned within the rightangular recess 8 of the main rail 7. The auxiliary rail, is inclined or flared upwardly 15 from its point of connection with the rail proper, beyond the crossing, so as to provide the central portion of the said auxiliary rail or that which is attached to the crossing proper, with a smooth bearing face. This bearing face is also adapted to receive the flanges of the wheel and to elevate the wheel proper above the head of the rail. It is to be understood that the transversely arranged auxiliary treads are arranged in a 20 plane parallel with each other, so that no interruption occurs when the said auxiliary rails are in position, and consequently the rolling stock passes over the crossing without contacting with the main rails, and this 25 avoids the thumping of the heels at the cut away portions of the said rails. The auxiliary tread 11 has its lower face provided with elongated slots 12, the said slots being vertically disposed and being arranged to 30 register with openings formed within the main rails 7. By providing the member 11 with elongated slots 12 it will be apparent that by merely loosening the retaining elements which secure the auxiliary rails to 35 the main rails the said auxiliary rail may be raised, strips of suitable material may be inserted within the lower face of the auxiliary rail and the horizontally straight portion of the continuous groove or depression 40 45 8 thus shoring the auxiliary rail to a desired position with relation to the tread of the main rail.

In Figs. 6 and 7 of the drawings, the rails are provided adjacent their heads and upon 50 one of their sides with a continuous longitudinally extending groove. The sides of the rails are curved outwardly to provide an enlarged base, and the base is formed with a continuous longitudinally extending 55 depression 10. The auxiliary rails 11 are adapted to be seated within the grooves upon the side or face of the rails, the auxiliary rails being provided with flanges 14. These flanges terminate at a suitable 60 distance away from the right angularly connected main rail members, the terminals of the flanges being flared outwardly and downwardly, as designated by the numeral 16. The auxiliary rails are provided with

transversely arranged elongated openings 65 through which pass the bolts 17 that coat with the nuts 18, whereby the said auxiliary rails may be shimmed to compensate for any wear upon the same.

In Fig. 8 of the drawings, I have illustrated 70 a rail of the construction similar to that described in connection with Figs. 4 and 5. In this instance, the auxiliary rail 19, is integrally formed upon its outer face with a flange 20. The auxiliary rail is secured to the main rail in any desired or preferred manner.

Having thus described the invention what I claim is:—

1. In a railway crossing superposed rail 80 sections consisting of a plurality of main rails formed right angularly and in one piece and having continuous grooves extending longitudinally of the inner faces of the said rails, and auxiliary rails formed right 85 angularly and in one piece adapted to be received in the said longitudinally extending grooves, each of the auxiliary rails having the upper faces of its terminals tapered downwardly and having the inner faces 90 flanged, the terminals of the said flanges being curved longitudinally, and means for sustaining the auxiliary rails upon the main rails.

2. In a railway crossing superposed rail 95 sections consisting of a plurality of main rails formed right angularly and in one piece and having continuous grooves extending longitudinally of the inner faces of the said rails, the sides of the said rails 100 being curved to form enlarged bases, the said bases being each provided with a centrally arranged longitudinally extending depression, and auxiliary rails formed right 105 angularly and in one piece adapted to be received in the said longitudinally extending grooves, each of the auxiliary rails having the upper faces of its terminals tapered downwardly and having the inner faces 110 flanged, the terminals of the said flanges being curved longitudinally, and means for 115 whereby the said auxiliary rails may be shimmed to retain their bearing faces at a predetermined distance from the heads of the main rails.

3. In a railway crossing superposed rail sections consisting of a plurality of main rails formed right angularly and in one piece and having continuous grooves extending longitudinally of the inner faces of the said rails, and auxiliary rails formed right 120 angularly and in one piece adapted to be received in the longitudinally extending grooves, each of the auxiliary rails having the faces of its terminals tapered downwardly and having the inner faces flanged, the terminals of the said flanges being 125 curved longitudinally, the said auxiliary

rails being further provided with vertically arranged elongated openings registering with openings in the main rails permitting shimming of the said auxiliary rails to retain their bearing faces at a predetermined distance from the heads of the main rails, and means passing through the elongated openings and openings in the main rails for sustaining the auxiliary rails upon the main rails.

In testimony whereof I affix my signature in presence of two witnesses.

GEORGE O. BRISTOW.
